(57) **CLAIM**

The ornamental design for a collectible display stand, as shown and described.

DESCRIPTION

FIG. 1 is a top perspective view of a collectible display stand, showing my new design in a used condition;

FIG. 2 is a top perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right-side view thereof, the left-side elevation view being a mirror image thereof; and,

FIG. 8 is a cross-section view thereof, taken along line 8-8 of FIG. 2.

The broken lines shown represent environmental subject matter and form no part of the claimed design.

1 Claim, 4 Drawing Sheets
